UNITED STATES PATENT OFFICE.

HARRY B. SNYDER, OF CHICAGO, ILLINOIS.

DESIGN FOR A HANDLE FOR CANES, &c.

SPECIFICATION forming part of Design No. 22,070, dated December 20, 1892.

Application filed November 23, 1892. Serial No. 452,957. Term of patent 3½ years.

To all whom it may concern:

Be it known that I, HARRY B. SNYDER, a citizen of the United States, residing at Chicago, in the county of Cook and State of Illinois, 5 have invented and produced a new and original Design for Cane, Umbrella, and Parasol Handles, of which the following is a specification, reference being had to the accompanying drawing, showing a part thereof.

10 My invention pertains to cane, umbrella and parasol handles such as may be preserved as mementos of the Columbian Exposition or World's Fair at Chicago.

15 In the drawing the figure represents the top part of my handle.

20 In the illustration the staff proper is represented as a mast which is capped by a ferrule, the upper extenuation of which represents a face and head of Christopher Columbus, the face and head of Columbus being similar to that in the De Bry portrait. Projecting from the ferrule are rings or bosses. Extending from the top of the ferrule in a curvilinear sweep and resting on the rings is the representation of a sail rope, the staff as 25 before remarked being intended to represent a mast. In the design the face of Columbus is beardless, and his head is covered with a wig which falls in waves at each side of his face, and is curly over the forehead. A cap 30 partially covers the wig.

It will be seen that I have provided a unique and attractive cane, umbrella and parasol handle which may be preserved as a souvenir.

Having thus described my invention what 35 I claim and desire to secure by Letters Patent is:—

The design for a cane, umbrella and parasol handle herein shown and described.

In testimony whereof I hereunto affix my 40 signature in the presence of two witnesses.

HARRY B. SNYDER.
